UNITED STATES PATENT OFFICE.

EUGENE F. LEWIS AND FRANK. T. WHALEY, OF NORWICH, CONNECTICUT.

PACKING FOR PISTON-RODS.

SPECIFICATION forming part of Letters Patent No. 444,002, dated January 6, 1891.

Application filed July 2, 1890. Serial No. 357,571. (No model.)

To all whom it may concern:

Be it known that we, EUGENE F. LEWIS and FRANK. T. WHALEY, both citizens of the United States, and residents of Norwich, in the county of New London and State of Connecticut, have made certain new and useful Improvements in Packing for Piston Rods, which improvements are fully set forth and described in the following specification, reference being had to the accompanying sheet of drawings.

This invention is in sectional packings for piston-rods, and has for its object certain improvements both in the form of the packing and in the manner of supporting the same.

15 In order to more clearly explain the construction of our improved packing we have annexed hereto suitable drawings, in which—

Figure 1 shows in longitudinal central section the several necessary parts of our device 20 properly assembled in a portion of a cylinder-head. Fig. 2 is an outer end view of the sectional packing removed, and Fig. 3 a cross-sectional view of the same on line *x* *x*. Fig. 4 is an inner end view of the cup-section, and 25 Fig. 5 a cross-section of the same on line *y* *y*. Figs. 6 and 7 show, respectively, an inner end and cross-sectional view on line *z* of the so-called “gland” *h*, against which the packing abuts at the outer end when the parts are assembled.

30 In the drawings, the letter *a* denotes a portion of a cylinder-head having its boss *b* bored to receive the piston-rod *c* and counterbored to receive the various parts of our packing.

35 The packing proper is formed of two rings, each made up of segments, those of one ring *d* being approximately L-shaped and those of the other or inner ring *d'* being of suitable shape to enter and fill the otherwise open annular space in the L-shaped ring.

We make no broad claim to a sectional packing consisting of an L-shaped ring and annular ring fitted therein, as such packing is old and well known; but we have improved 45 somewhat such packings by making the inner ring *d'* somewhat conical at its periphery and have correspondingly shaped the inner wall of the outer ring, as plainly shown in Figs. 1 and 3. We find in practice that the 50 slightly-conical bearing-surfaces thus provided between the two rings insures a more

perfect fit as the several segments become worn and seek to close concentrically upon the piston-rod.

In our present form of packing we provide 55 an encircling flat spring *e*, that is made thickest at the point opposite its opening. When in use, a spring of this form allows the several segmental sections to open and close more uniformly than when a spring of the same 60 thickness throughout its length (as of wire) is used, thus distributing the wear on the ring-packings through the entire series of segments, instead of concentrating it on one or two segments, as heretofore. 65

We prefer making one end of the packing cone-shaped to enter a cupped seat in a washer *f*, that is located when the parts are assembled between the packing proper and a spring *g* at the bottom of the counterbored cavity in 70 the cylinder-head. The outer or flat face of the sectional packing rests against the inner face of the so-called “gland” *h*, and with the aid of spring *g* forms a steam-tight joint, although left free to move laterally as the piston-rod works through it. Gland *h* is held 75 rigidly by a plate *m*, bored to fit over two or more bolts *i*, projecting from boss *b*, and is firmly secured in place by nuts *k*. The openings in the gland and cylinder-head are somewhat larger than the piston-rod, thus avoiding 80 all possibility of binding or cramping of said rod if slightly deflected in its movement through said gland and cylinder-head, and the manner of supporting the segmental packing allows it to follow any such deflection of the rod and prevents undue friction. The inner face of the gland is provided with a rabbet or groove *h'*, which forms two shoulders, one of which fits within the outer end of 85 the counterbore in the boss and centers the gland and the other shoulder abuts against the outer face of the boss, whereby the gland is rigidly held by the plate *m*, which forces the shoulder against the outer end of the boss. 90

The conical end of the segmental packing, coacting with the cupped washer *f*, serves to concentrate the several segments as they are worn by the piston-rod, while the outer (flat) end of said packing coacts with the inner face 100 of the gland and forms a steam-tight joint.

It is obvious that gland *h* and plate *m*

could be made as a single piece; but we prefer to make them separate, as we are then able to use brass or similar metal for the gland to coact with the segmental packing 5 and steel or iron for the plate *m*.

Having thus described our invention, we claim—

In a packing for piston-rods, the combination, with a counterbored boss, of a spring in 10 the bottom of the counterbore, a washer having a flat face resting against the spring and having its opposite face provided with a cupped seat, a segmental outer ring, one end of which is conical and fits within the cupped

seat of the washer, and the opposite end is 15 provided with a conical counterbore, a cone-shaped segmental inner ring within the counterbore of the outer ring, the outer faces of said rings being flat, means for forcing the segments of the rings inward, a flat-surfaced 20 gland fitting against the flat faces of the rings, and a plate for holding the gland and packing in position, substantially as described.

EUGENE F. LEWIS.
